UNITED STATES PATENT OFFICE.

MAURUS C. RECK, OF ROCHESTER, NEW YORK, ASSIGNOR TO SILL STOVE WORKS, OF ROCHESTER, NEW YORK, A CORPORATION OF NEW YORK.

DESIGN FOR A STOVE-OVEN SUPERSTRUCTURE.

Application filed September 2, 1922. Serial No. 3,623. Term of patent 14 years.

To all whom it may concern:

Be it known that I, MAURUS C. RECK, a citizen of the United States, residing at Rochester, in the county of Monroe and State of New York, have invented a new, original and ornamental Design for Stove-Oven Superstructures, of which the following is a specification, reference being had to the accompanying drawing, forming part thereof.

The figure is a perspective view of a stove oven superstructure, showing my new design.

I claim:

The ornamental design for a stove oven superstructure, as shown.

MAURUS C. RECK.
